UNITED STATES PATENT OFFICE.

THOMAS CORROW, OF SWAMPSMOT, MASSACHUSETTS, ASSIGNOR TO UNITED SHOE MACHINERY COMPANY, OF PATERSON, NEW JERSEY, A CORPORATION OF NEW JERSEY.

SOLE-ROUNDING MACHINE.

1,177,021.

Specification of Letters Patent. Patented Mar. 28, 1916.

Application filed February 15, 1915. Serial No. 8,303.

To all whom it may concern:

Be it known that I, THOMAS CORROW, a citizen of the United States, residing at Swampscott, in the county of Essex and State of Massachusetts, have invented certain new and useful Improvements in Sole-Rounding Machines; and I do hereby declare the following to be a full, clear, and exact description of the invention, such as will enable others skilled in the art to which it appertains to make and use the same.

The invention relates to machines for rounding or for rounding and channeling the soles of shoes after the outer sole has been temporarily secured in position preparatory to permanently sewing or otherwise securing it to the shoe.

The invention is intended primarily as an improvement in the rounding and channeling machine shown and described in Patent No. 1,030,606, June 25, 1912, although it may be embodied with advantage in other machines. In the machine of the above patent the shoe is guided during the operation through the shank of the shoe by a crease guide and is guided during the operation about the forepart by a forepart guide which is normally in raised or inactive position, and which is moved into and out of active position by the operator in passing from the shank to the forepart or from the forepart to the shank. The crease guide is so mounted that it may be moved with the forepart guide during the period that the forepart guide is in action, and the crease guide and forepart guide are provided with cooperating stops which are brought into engagement by the movement of the forepart guide into active position, and which serve to determine the position of the forepart guide relatively to the crease guide, and to connect the guides so that they move in unison during the time that the forepart guide is in action. The forepart guide is vertically adjustable on its carrier so that it may be adjusted to vary the projection formed on the sole during the rounding, and the stop which determines the position of the forepart guide is connected to move with the forepart guide when the forepart guide is thus adjusted, and is also independently adjustable with relation to the forepart guide.

In doing certain classes of work it may be

desirable to utilize the crease guide for guiding the shoe about the forepart as well as through the shank, and one of the objects of the present invention is to provide means by which this result may be readily and conveniently secured.

It is also an object of the invention to provide means whereby the relative movement between the forepart guide and crease guide as the forepart guide is thrown into operation may be determined independently of the coöoperating stops above referred to, in case such independent adjustment may be found desirable for any reason.

With the above objects in view, the invention comprises the features of construction and combinations of parts hereinafter described and referred to in the claims.

The invention will be readily understood from an inspection of the accompanying drawings and the following detailed description of the mechanism illustrated therein.

In the drawings, Figure 1 is a sectional elevation of so much of the rounding and channeling machine shown and described in the patent above referred to as is necessary to illustrate the application of the present invention thereto; Fig. 2 is a detailed side elevation showing the forward ends of the crease guide and forepart guide and their carriers; Fig. 3 is a front elevation of the parts shown in Fig. 2; and Fig. 4 is a detailed perspective view showing the stops which are secured to the crease guide.

The machine shown in the drawings is provided with a crease guide 2 secured to the forward end of the pivoted carrier arm 4, and with a forepart guide 6 mounted upon the forward end of the pivoted carrier arm 8. The crease guide is held in normal position by the spring 10, and is free to move downward against the tension of the spring when the forepart guide is moved down into active position. The forepart guide carrier 8 is held normally in its raised or inactive position, and is thrown into and out of action by the operator in the manner fully described in the patent above referred to. When the forepart guide is in action its position is controlled by one of a series of pattern cams carried by the pattern cam shaft 12, as fully described in the patent above referred to.

The forepart guide 6, which is brought

into position to engage the upper close to the crease in passing from the shank to the forepart of a shoe, is in the form of an arm which is pivotally connected to the lower 5 end of a vertically adjustable slide 14 mounted in the front end of the carrier arm 8. The upper end of the slide 14 is provided with a laterally extending arm 16 which carries an adjustable stop screw 18 arranged 10 to engage a coöperating stop 20 on the crease guide when the forepart guide is brought into operation, so that the crease guide will move with the forepart guide during the operation around the forepart of the shoe. 15 The screw 18 may be adjusted to determine the position of the forepart guide with relation to the crease guide when the screw is in engagement with the coöperating stop 20, and to determine the movement of the fore- 20 part guide with relation to the crease guide before the stops are brought into engagement and act to connect the guides so that they will thereafter move in unison.

The slide 14 may be adjusted on the carrier 8 to vary the position of the forepart guide and the stop screw 18 with relation to the carrier 8, and thus secure the desired projection of the sole around the forepart of the shoe. The devices for securing this 30 adjustment comprise an operating and latch lever 22 secured to the end of a rock shaft 24 which is connected to move the slide 14 vertically through a crank pin and slot connection, as fully described in the patent 35 above referred to. The adjustment of the forepart guide to secure the desired projection of the sole does not affect the position of the forepart guide with relation to the crease guide during the operation of the forepart guide, since the stop 18 moves with the forepart guide when the forepart guide is adjusted.

In embodying the preferred form of the invention in a machine having the construction 45 above described, a second and independently adjustable device is provided for determining the movement of the forepart guide carrier with relation to the crease guide and its carrier when the forepart 50 guide is moved into operation, and for causing the guides to move in unison while operating about the forepart of a shoe. In the construction shown, this device comprises an adjustable stop screw 26 mounted on the 55 crease guide carrier and arranged so that it may be adjusted into or out of position to be engaged by the forepart guide carrier 8 when the forepart guide is moved down into action. For convenience in manufacture the screw 26 is mounted in a projecting lug 28 formed on a clip 30 which may be secured to the crease guide or its carrier, and which is also provided with a projecting lug forming the stop 20. The screw 26 may be 60 adjusted vertically into such position that

it will be engaged by the forepart guide carrier 8 before the forepart guide reaches the shoe. In such case the crease guide will continue to guide the shoe throughout the operation about the forepart, and will be 70 moved and controlled by the pattern cam to give the desired form to the projecting edge of the sole. In this case the stops 18 and 20 are not brought into engagement, and are consequently rendered inactive. 75 The screw 26 may be rendered inactive by adjusting it vertically into such position that the stops 18 and 20 are brought into engagement before the carrier 8 reaches the screw. In this case the stops 18 and 20 are 80 active, and the forepart guide engages and guides the shoe, the crease guide moving with the forepart guide while the forepart guide is in action. The screw 26 may be secured in adjusted position by the lock 85 nut 32.

While it is preferred to employ the specific construction and arrangement of parts shown and described, and to mount the stop screw 26 upon the crease guide, it will be 90 understood that this construction and arrangement is not essential to the broader features of the invention, and may be varied or modified as found desirable or best suited to the construction of the machine in which 95 the invention is to be embodied.

Having explained the nature and object of the invention, and specifically described one form of mechanism in which it may be embodied, what is claimed is:—

100

1. A sole rounding machine, having, in combination, a crease guide, a forepart guide, and two independently adjustable devices for causing the crease guide and forepart guide to move together when the forepart guide is moved into action.

2. A sole rounding machine, having, in combination, a crease guide, a forepart guide, two devices for causing the crease guide and forepart guide to move together 110 when the forepart guide is moved into action, and means whereby the devices may be rendered alternatively active.

3. A sole rounding machine, having, in combination, a forepart guide movable 115 into and out of operation, a crease guide mounted to move with the forepart guide when the forepart guide is in action, means for adjusting the forepart guide to vary the projection of the sole edge, a stop adjustable 120 with the forepart guide for determining the position of the forepart guide with relation to the crease guide when the forepart guide is in operation, and an independently adjustable stop for determining the position of 125 the forepart guide with relation to the crease guide when the forepart guide mechanism is in action.

4. A sole rounding machine, having, in combination, a vertically movable crease 130

guide carrier, a vertically movable forepart guide carrier, a forepart guide vertically adjustable on its carrier, a stop adjustable with the forepart guide and independently thereof, a coöperating stop on the crease guide carrier, and a stop on the crease guide carrier adjustable into and out of position

to be engaged by the forepart guide carrier.

Copies of this patent may be obtained for five cents each, by addressing the "Commissioner of Patents,
Washington, D. C."

It is hereby certified that in Letters Patent No. 1,177,021, granted March 28, 1916, upon the application of Thomas Corrow, of Swampscott, Massachusetts, for an improvement in "Sole-Rounding Machines," an error appears in the printed specification requiring correction as follows: Page 1, strike out line 49 and insert the words *part guide with relation to the crease guide*; and that the said Letters Patent should be read with this correction therein that the same may conform to the record of the case in the Patent Office.

Signed and sealed this 25th day of April, A. D., 1916.
